(57) **CLAIM**

The ornamental design for a camera, as shown and described.

DESCRIPTION

FIG. 1 is a front perspective view of a camera, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged portion view taken from encircled portion labeled, “9,” in FIG. 3; and,

FIG. 10 is an enlarged portion view taken from encircled portion labeled, “10,” in FIG. 3.

The dashed-dot lines form the boundary of the enlarged portion views of FIGS. 9–10 in FIGS. 3 and 9–10 and form no part of the claimed design. The even dashed broken lines shown in the drawings are included for the purpose of illustrating portions of the camera that form no part of the claimed design.
